UNITED STATES PATENT OFFICE.

ERNEST PULSFORD, OF NUTLEY, NEW JERSEY.

CABLEWAY.

1,178,943.

Specification of Letters Patent. Patented Apr. 11, 1916.

Application filed August 12, 1914. Serial No. 856,386.

To all whom it may concern:

Be it known that I, ERNEST PULSFORD, a citizen of the United States, residing at Nutley, in the county of Essex and State 5 of New Jersey, have invented certain new and useful Improvements in Cableways, of which the following is a specification.

My invention relates broadly and generally to new and useful improvements in 10 cableways of that character or type employed for hoisting and transporting loads and employing a carrier or carriers for supporting the operating line or lines for hoisting or transporting the load.

15 In cableways of moderate length of span where a carrier is required between the carriage and tower to support the hoisting or fall-rope, it has been customary to employ carriers of the differential type, as exemplified in the patents of Charles M. North No. 480,029, August 2, 1892, and Spencer Miller No. 901,021, October 13, 1908, Reissue No. 12,962, June 8, 1909. These differential carriers are propelled by the frictional engagement of the conveying rope with a sheave of the carrier causing same to roll upon the main cable and move the carrier at one half the speed of the carriage, thus dividing the space between the carriage and tower into 25 two equal spaces. The difficulty with these carriers is that unless the conveying rope is caused to bear with considerable pressure on the sheave the carriers slip and fail to register properly. And if the pressure is 30 sufficient the carriers are very destructive to the rope. To obviate these difficulties I have invented a carrier which is positively propelled at a definite speed relative to the speed of the carriage, for example at one 35 half the speed of the carriage. In one embodiment of my invention, hereinafter described, I accomplish this by attaching a conveying rope to the carrier and propel the carriage by the carrier by providing a 40 connection of variable length between the carrier and the carriage.

The invention consists in the improvements to be more fully described hereinafter and the novelty of which will be particularly pointed out and distinctly claimed.

50 I have fully and clearly illustrated my

invention in the accompanying drawings to be taken as a part of this specification and wherein:

Figure 1 is a diagrammatic view in perspective showing a preferred form of cableway constituting one embodiment of my invention. Fig. 2 is a view in side elevation of the head of a tower for supporting the cableway and showing the relative positions 55 of a load carriage and a fall-rope carrier in a cableway constructed and operated according to my invention. Fig. 3 is a view in elevation of a rope carrier constructed in accordance with my invention. Fig. 4 is a 60 view in elevation of a load carriage.

Referring to the drawings by characters of reference: 1 designates a main cable the ends of which are connected to, and supported by, a head tower 2 and a tail tower 3. 70 The construction of said towers is immaterial as long as they will serve the purposes for which they are employed and I, therefore, do not deem it necessary to enter into any detailed description thereof. It will be 75 understood that the main cable may be supported from these towers in any of the ways well known in the art. Adapted to travel upon this main or supporting cable is a load carriage 4 consisting preferably of vertical 80 parallel side plates 5, 6, carrying, at their upper ends, bearing pins 7 upon which revolve grooved running wheels 8 adapted to travel upon the main cable 1, the latter, during the operation of the carriage, being located in the space between side plates 5, 6. 85 At their lower portions the said plates 5, 6, are connected by bearing pins 9, upon which are mounted grooved pulleys or sheaves 10 over which passes a hoisting or fall-rope 11, 90 having one end connected to the tail tower, as at 12, and the other end passing over a sheave or pulley 13 mounted on the head tower, whence said rope passes down to the drum 14 of any suitable type of winding 95 engine which is adapted to take up and pay out said fall-rope. The hoisting or fall-rope 11 is provided with a loop or bight 15 which depends from the load carriage between the said pulleys 10, said bight supporting the pulley 16 of a block from which the load, for instance a bucket 17, is adapted 100

to be suspended. The arrangement of the fall-rope is such that the drum 14 may be operated to take up or pay out the fall-rope, thereby raising or lowering the load, and the carriage may then be traversed lengthwise of the main cable by means to be hereinafter described. The carriage is provided on opposite sides thereof with plates 19, 20, spaced, respectively, from the plates 5, 6, 10 heretofore described, and between each of said plates 19, 20, and the adjacent plates 5, 6, are journaled upper and lower grooved guide-rollers 21, 22, for a purpose to be hereinafter set forth.

15 I will now proceed to describe the fall-rope carrier construction and arrangement for supporting the hoisting or fall-rope 11 between the carriage and the supporting towers, and for causing the carriers to take 20 a definite position relative to the carriage. In the embodiment shown and hereinafter to be described, I employ two carriers located, respectively, on opposite sides of the carriage between the latter and the supporting towers, and provide means whereby the 25 carriage and the carriers travel at definite speeds relative to each other so that the carriers are always located substantially midway between the carriage and the support 30 for all positions of the carriage. These carriers consist preferably of frames comprising vertical spaced parallel plates 23, 24, connected at their upper ends by a pin 25, upon which is journaled a grooved roller 35 26 located in the space between said plates 23, 24, and adapted to travel upon the main cable, the latter passing in the space between said plates 23, 24. Mounted on one 40 side of the carrier frame is a vertically disposed plate 27 spaced from the plate 24 and having its upper end mounted on the pin 25 and its lower end connected to the lower portion of the plate 24 in any suitable manner, as, for instance, by a rivet 28. Bridging 45 the space between the plate 24 and the plate 27 is a bearing pin 29 upon which is journaled a grooved pulley 30, for a purpose to be presently described. On the opposite side of the carrier frame from the one supporting the pulley 30 is a vertical plate 31 50 connected at its upper end to said pin 25, and at its lower end connected to the plates 23 and 24 by a cross-pin or bolt 32, upon which are mounted spacing sleeves 33 for 55 maintaining the said plates 23, 24, and 31 in proper spaced parallel relation. Located at the lower portion of the frame and bridging the spaces between the plates 23, 24, and 31 is a bearing pin 34 upon which are 60 mounted grooved pulleys 35, 36, there being a pulley in each of the spaces, as clearly shown in Fig. 3 of the drawings. Mounted on the ends of the pin 29, heretofore described, are the arms 37 of a yoke 38, which

serve a purpose to be presently described. 65 As both of the fall-rope carriers are of the same construction, the description of one will suffice.

Connected to the yoke 38 of the fall-rope carrier, located between the carriage and the tail tower, as at 39, is one end of a traversing rope 40, which may be termed the "outhaul" rope, the latter passing from said fall-rope carrier under a pulley 41 and over a pulley 42 mounted on the tail tower, said 70 rope 40 passing from the pulley 42 lengthwise of the cableway toward the head tower and over a pulley 43 mounted on the latter, whence it passes down to, and is wound upon, the drum 44 of a winding engine. 75 80 This rope is operable, by the drum 44, to pull or traverse the fall-rope carrier to which it is connected toward the tail tower. The yoke 38 of the fall-rope carrier located between the load carriage and the head 85 tower is connected to a line 45, which may be termed the "inhail" line, said line extending over a pulley 46 on the head tower and down to said drum 44, upon which it is wound in a reverse direction to the line 40, 90 so that, when said drum is operated to take up one of said lines, the other is paid out. It will be apparent that, when the line 45 is wound on the drum 44, the fall-rope carrier to which said line is connected will 95 be pulled toward the head tower, while the line 40 will be paid out to permit the other fall-rope carrier also to travel toward the head tower by virtue of means to be presently described, and, when the reverse operation takes place, the line 40 will pull its fall-rope carrier toward the tail tower, while the line 45 will be paid out to permit its fall-rope carrier to move toward the tail tower by means which I will now describe. 100 105

Means is provided whereby the operation of one of the traversing lines to traverse the fall-rope carrier to which it is connected will cause the load carriage to travel along the main cable with the fall-rope carrier 110 and preferably at a speed greater than that at which the fall-rope carrier travels, which means will now be described. Connected to the carriage, for instance at the point 47, is a line 48 which passes from the carriage 115 lengthwise of the cable to and over the grooved pulley 30, heretofore described, mounted on the fall-rope carrier, said rope 48 being reversed upon itself and carried between the grooved pulleys 21, 22, on one 120 side of the load carriage, thence to and over one of the pulleys 35 on the other carrier, and thence to the tail tower, where it may be fixed or anchored, as at 49. By this arrangement, the operation of the fall-rope 125 carrier by the line 45, to travel toward the head tower, will, by virtue of the line 48, cause the carriage to travel toward the head

tower simultaneously with the fall-rope carrier and at a definite speed relative thereto, the connection shown serving to cause the carriage to travel at twice the speed of the fall-rope carrier, so that the fall-rope carrier is always located at a point substantially midway between the head tower and the carriage. The fall-rope carrier on the opposite side of the carriage—that is, the one located 5 between the carriage and the tail tower, may be connected to the carriage in a manner similar to that just described. By a line 48^a connected to the carriage, as at 48^b, and passing therefrom over the sheave 30 on the fall-rope carrier between the carriage and the tail tower, thence reversed upon itself and carried lengthwise of the cableway and passed between the pulleys 21, 22, on the opposite side of the carriage from those engaged by the rope 48. From the carriage 10 the rope 48^a passes over one of the pulleys 35 on the fall-rope carrier located between the carriage and the head tower, and is connected to the head tower, as at 49^a. When 15 said fall-rope carrier is moved toward the tail tower, the carriage will follow it at a definite speed and in a definite relation—that is in the embodiment shown at twice the speed of the fall-rope carrier, and the fall-rope carrier will always be midway the tail 20 tower and the carriage. It will also be seen that the fall-rope carrier located between the carriage and the head tower will follow the carriage at one-half the speed of the latter, so that it too will always be definitely 25 located one-half the distance between the carriage and the head tower.

It is believed the operation of the invention will be understood from the above description, but it may be stated as follows, it being premised that the parts are in the position shown in Fig. 1, and that the load 17 is to be raised and traversed lengthwise of the cableway: The drum 14 is operated to 30 wind the line 11 thereon, which operation serves to take up or shorten the bight or loop 35 and thereby raise the load. When the load has reached the desired height, the drum 14 may be held under brake and the carriage, with the load suspended therefrom, may then be traversed lengthwise of the cableway in either direction. If the carriage 40 is to be hauled toward the head tower, the operator causes the drum 44 to turn in the proper direction to take up the line 45 and pay out the line 40, which will cause 45 the line 45 to haul the fall-rope carrier to which it is directly connected toward the head tower, which in turn will serve to pull 50 the carriage toward the head tower simultaneously with said fall-rope carrier, and at twice the speed due to the fact that the fall-rope carrier and carriage are connected by the carrier engaging a bight of the rope 48,

which rope has one end fixed and the other 65 end attached to the carriage. During the movement described the fall-rope carrier will always be located at a position substantially equidistant between the carriage and the head tower and the fall-rope will be properly supported at the most advantageous point. While the operation just described is taking place, the carriage will take up the line 48^a, which will cause the fall-rope carrier between the carriage and the tail tower 70 to follow the carriage at one-half the speed at which the carriage travels, due to the fact that the line 48^a is doubled upon itself, one branch of which is a standing rope similar to the rope 48, such movement of the carrier 75 being permitted, due to the fact that the line 40 is being paid out. When the load is to be traversed in the opposite direction from that described, the drum 44 is operated to take up the line 40 and pay out the 80 line 45 so that the fall-rope carrier connected directly to the rope 40 moves toward the tail tower and, by virtue of the connection 48^a, causes the carriage to follow it at double 85 its speed. During this operation, the line 90 45 being paid out, the carriage takes up the line 48 to cause the carrier connected to said line 45 to follow the carriage at a speed one-half the latter.

It will be seen that the traversing movements of the carriage are effected by pulls of the traversing lines exerted on the fall-rope carriers, and that the lines 48, 48^a, constitute differential speed connections between the fall-rope carriers and the carriage whereby the carriage and the fall-rope carriers are traversed at a definite relative speed and are compelled to maintain the same relative position throughout the traversing movement.

While the preferred embodiment is particularly adapted to short span cableways employing a single carrier between carriage and tower, constructed to cause the carriage to travel at twice the speed of the fall-rope carriers, I do not desire to be limited either as to the number of carriers or this exact relative speed, as the connection between the carriers and the carriage may be modified, or other differential speed connections substituted therefor, to cause the carriage to travel at a greater or less speed than twice the speed of the fall-rope carriers, without departing from the spirit and scope of my invention.

What I claim and desire to secure by Letters Patent of the United States is:—

In combination, a supporting cable, a carriage on said cable, a fall-rope passing over the carriage, a fall-rope carrier on each side of said carriage and movable lengthwise of the supporting cable, a sheave mounted in each of said fall-rope carriers,

two ropes each of which is secured to a fixed support at one end of the path of travel of the carriage, and extends to the opposite side of the carriage over the sheave of one fall-rope carrier and thence back to the carriage to which it is secured, and a traversing rope for the carriage, the said rope being secured at one end to a fall-rope carrier, and thence extending over a winding 10 drum and back past the fall-rope carriers

and carriage and over a suitable sheave and extending from the latter to the second fall-rope carrier, to which it is secured.

In testimony whereof I have hereunto signed my name in the presence of two sub- 15 scribing witnesses.

ERNEST PULSFORD.
